Attorney

UNITED STATES PATENT OFFICE.

GEORGE A. RIPLEY, OF DALLAS, TEXAS.

BUTTON MOUNTING FOR GARMENTS.

Application filed September 30, 1924. Serial No. 740,707.

To all whom it may concern:

Be it known that I, GEORGE A. RIPLEY, a citizen of the United States of America, residing at Dallas, in the county of Dallas and State of Texas, have invented certain new and useful Improvements in Button Mountings for Garments, of which the following is a specification.

This invention relates to new and useful 10 improvements in button mountings for garments.

The method of fastening buttons on shirts, waists and other garments, which is now in common use, is not such as to prevent the 15 buttons from being rather easily torn off. For this reason very few garments survive the laundry without losing one or more buttons. It is the common practice to sew through the cloth and a single thickness of 20 tape applied to underside of the edge of the garment.

The object of my invention is two-fold and is first, to mount the button so that it cannot be torn off even under the most severe 25 conditions; and second, to provide such a mounting in the most simple and economical manner adequate with competitive manufacture.

A further object is to provide such a 30 mounting and practice the invention without increasing the labor cost and to keep the increase in the cost of material at minimum.

A construction designed to carry out the 35 invention will be hereinafter described together with other features of the invention.

The invention will be more readily understood from a reading of the following specification and by reference to the accompanying drawings, in which an example of the 40 invention is shown, and wherein:

Fig. 1 is a view of a portion of the front of a shirt broken away to show buttons mounted in accordance with this invention, and

Fig. 2 is an enlarged cross-sectional view 45 on the line 2—2 of Fig. 1.

In the drawings the numeral 10 designates the front of a shirt and 11 a hem which is folded under along the edge of the fabric.

50 A facing strip 12 has a narrow hem 13 along

its outer edge complementary to the hem 11. The facing strip may be made of tape or other material and is applied to the under or inner side of the fabric with its hem 13 in contact with the hem 11. These hems are 55 united along the edge of the garment by a row of stitches 14.

The strip 12 has a hem 15 folded inward along its inner edge and contacting with the fabric along the hem-fold by a row of 60 stitches 16. The hem is provided with an extended ply 17 directed toward hems 11 and 13 and lying between the strip and the fabric. It will be seen that to produce this extension it is merely necessary to employ a strip or tape sufficiently wide to provide the extension when the fold is made. It is customary to provide the hem 16, but not the extension and therefore only the additional 65 material is required and the labor cost is not increased.

The button 18 is attached by passing the thread 19 through the fabric 10, the extension 17 and the strip 12, whereby it is attached to three plies of fabric. Actual tests have shown that the average person is 70 unable to pull off a button mounted in this manner. The extension provides the reinforcing and is the essence of the invention.

Various changes and alterations may be 75 made within the scope of the appended claim.

What I claim, is:

As an article of manufacture, a garment having a button mounting comprising a facing strip provided with a narrow hem along its outer edge stitched to the edge portion of the fabric of the garment at a closure thereof and an inwardly folded wider hem forming a free extension of substantially 85 one half of the width of the strip and lying between the strip and the fabric, stitching securing both hems of the strip to the garment at their folded edges, and buttons mounted on the fabric and secured by 90 threads passing through the three-ply provided by the fabric, the free hem extension and the strip.

In testimony whereof I affix my signature.

GEORGE A. RIPLEY.
